WIRING CONNECTOR SOCKET

Leslie O. Parker, Anderson, Ind., assignor to General Motors Corporation, Detroit, Mich., a corporation of Delaware

Application March 24, 1941, Serial No. 384,837

1 Claim. (Cl. 173—269)

This invention relates to the manufacture of electrical connectors and more particularly to the type of electrical connector for use on automotive vehicles.

It is an object of the invention to provide an electrical connector of simple and inexpensive construction which may be manufactured at low cost.

Further objects and advantages of the present invention will be apparent from the following description, reference being had to the accompanying drawing wherein a preferred embodiment of the present invention is clearly shown.

In the drawing:

Fig. 1 is a perspective view of a strip of material in the process of progressive formation for providing the metallic part of an electrical connector disclosed in the present invention.

Fig. 2 is a perspective view of a wire having attached thereto one of the connectors severed from the strip of material shown in Fig. 1.

Fig. 3 is a perspective view of a wire attached to a plug adapted to be received by the connector shown in Fig. 2.

Fig. 4 is a perspective view showing an insulating tube enclosing the connector attached to the wire shown in Fig. 2.

Fig. 5 is a perspective view of the wire and insulating tube after the tube has been deformed by the action of heat and pressure so as to become permanently attached to the connector and wire.

Fig. 6 is drawn to a larger scale than the preceding figures, shows a longitudinal sectional view of the insulating tube, metal connector and wire, all of these parts being permanently attached to each other.

Fig. 1 shows a strip of metal 20 which has been sheared and bent progressively to form connector socket members 21. The various stages are indicated by the brackets associated with small letters a, b, c, c, and d. A wire bared of its insulation is placed between the prongs 22 and 23. The last operation of the machine which punches and forms the strip 20 causes the tangs 22 of connector plug 21 to be folded against the bared portion of the wire indicated at 24. The tangs 23 of the connector plug are folded around the insulating portion 25 of the wire. This operation is accompanied by the operation of severing the section d from remaining portions of the strip 20. The machine for performing these operations is similar to the machine described and claimed in Patent No. 2,169,802 granted to General Motors Corporation by C. J. Keller.

The bared portion 24 of the wire is attached to the connector 21 also by the means of solder indicated at 26. Also the connector 21 is provided with resilient ears 27 which are spaced apart a distance less than the diameter of the portion 28 of connector plug 30 attached to wire 31 as shown in Fig. 3. The spacing of ears 27 is greater than the diameter of the tip end 29. When the plug 30 is pressed into the connector socket 21, the ears 27 spread apart to allow spherical bosses 32 on the interior sides of the ears to ride over the surface 28 into plug 30 and to allow these bosses 32 to be received by the annular groove 33 of the plug 30. In this way, the withdrawal of the plug 30 from the socket 21 is yieldably resisted since the withdrawal of the plug from the socket requires that the ears 27 must spread apart a distance such that the bosses 32 may ride over the large portion 28 of the plug 30.

In order to prevent contact between the connected plug and socket with a metallic part such as the automobile frame and thus to prevent a short circuit, the socket 21 is enclosed by tube 40 formed preferably of thermo-plastic material and having a length sufficient to enclose both the socket and the plug. The tube is of such cross sectional contour and has such dimension that it will clear the resilient ears 27 and thus not interfere with the spreading thereof when the plug is pushed into the socket. While the tube 40 is located in the proper position relative to the socket 21, the portion of the tube 40 immediately adjacent the bared wire portion 24, the tangs 22 and 23 and the insulation 25 is deformed by the application of heat and pressure to cause a portion of the material and the tube to envelop the tangs 22, 23 and the insulation 25 in order to permanently attach the tube 40 to the wire and connector socket as shown in Fig. 6.

I have, therefore, provided for the economical manufacture of a connector socket and for the attachment thereto of an insulated wire. The socket member is a one piece construction fabricated from a strip of sheet metal, and is attached to the wire during the last operation of forming the socket and severing it from the supply of socket formed material. The socket is encased in a one piece non-conducting tube made from one of the well-known thermoplastic plastics such as "Tenite." The subjection of one portion of this tube to the application of each pressure causes its wall to be deformed and squeezed around the connector socket and insulated part of the wire. An efficient and durable connector

socket has, therefore, been provided at very low cost.

While the embodiment of the present invention as herein disclosed, constitutes a preferred form, it is to be understood that other forms might be adopted, all coming within the scope of the claim which follows:

What is claimed is as follows:

The method of making a connector and cable assembly which comprises forming a connector, attaching it to the insulated and bared portion of the cable, placing a tube of non-conducting thermo-plastic material around the connector and cable, said tube having such internal dimensions as to provide clearance for the con- 15

10 nector, a portion of the tube surrounding the connector and extending beyond the free end thereof and a portion of the tube extending around the cable and that portion thereof attached to the connector, and in constricting that portion of the tube which surrounds the cable and parts thereof attached to the connector by application of heat and pressure to cause said portion of the tube to conform to the insulation of the cable and the parts of the connector directly attached to the cable while that part of the tube surrounding the portion of the connector which extends from the cable remains in the original shape.

LESLIE O. PARKER.
